UNITED STATES PATENT OFFICE.

JULYE MYERS, OF BOSTON, MASSACHUSETTS.

SALVE.

SPECIFICATION forming part of Letters Patent No. 224,031, dated February 3, 1880.

Application filed November 1, 1879.

To all whom it may concern:

Be it known that I, JULYE MYERS, of Boston, in the county of Suffolk and State of Massachusetts, have invented a new and useful 5 Salve Compound, of which the following is a specification.

My invention has for its object to provide a salve for the curing of sores, boils, felonies, abscesses, burns, scalds, and other cutaneous diseases and injuries; and it consists of a combination of the following ingredients, viz: iodine, turpentine, camphor, glycerine, olive-oil soap, bees-wax, shoe-makers' wax, and lard.

The relative proportions of these ingredients 15 may be varied somewhat; but I have found that satisfactory results are obtained by the use of the following proportions, by weight, viz: iodine, one-eighth of an ounce; turpentine, one-eighth of an ounce; camphor, one- 20 eighth of an ounce; glycerine, three-eighths of an ounce; olive-oil soap, one-fourth of an ounce; bees-wax, one-fourth of an ounce; shoe-makers' wax, one-half ounce; lard, five-eighths of an ounce.

25 The salve is made by first melting the solid ingredients, and then mixing with them the

liquid ingredients until all are thoroughly commingled. The salve is then put into boxes and is ready for use.

In some cases I may dispense with the olive-oil soap and substitute olive-oil for it, and I consider olive-oil an equivalent for olive-oil soap.

It is common to employ iodine and lard in making ointments, and it is not new to make 35 a liniment of iodine, turpentine, camphor, alcohol, sweet-oil, and capsicum; but these compounds are different from my salve, not only in composition but also in effect.

I claim—

40 The described salve compound, consisting of iodine, turpentine, camphor, glycerine, olive-oil soap or its equivalent, bees-wax, shoe-makers' wax, and lard, as set forth.

In testimony whereof I have signed my 45 name to this specification, in the presence of two subscribing witnesses, this 30th day of October, 1879.

JULYE MYERS.

Witnesses:
